UNITED STATES PATENT OFFICE.

BERT C. SUITS, OF INDIANAPOLIS, INDIANA, ASSIGNOR OF ONE-HALF TO JOSEPH LEDERER, OF NEW YORK, N. Y.

AUTOMATIC SAFETY-GATE FOR RAILWAY-CROSSINGS.

1,116,157.

Specification of Letters Patent

Patented Nov. 3, 1914.

Application filed March 16, 1914. Serial No. 825,142.

To all whom it may concern:

Be it known that I, BERT C. SUITS, a citizen of the United States, residing at Indianapolis, in the county of Marion and State of Indiana, have invented certain new and useful Improvements in Automatic Safety-Gates for Railway-Crossings, of which the following is a specification.

This invention relates to a safety gate for protecting intersections of streets and highways with railway crossings; and the object of the invention consists in the provision of a safety gate for protecting the intersections of streets and highways with railway crossings which is operated by the train on approaching the crossings by lowering the gate and for raising the gate when the engine has passed the highway allowing the gate to raise and remove the obstruction by the time the train has cleared the crossing.

A further object of the invention consists in the provision of a safety gate for protecting street and highway intersections with railways in which the gate is lowered at a predetermined rate of speed, it being immaterial at what rate of speed the train is traveling when the tripping device is actuated, thereby eliminating any danger to the working parts of the apparatus.

A further object of the invention consists in the provision of a safety gate at intersections of streets and highways with railway crossings, which is simple in construction, cheap to manufacture and install, and efficient in operation.

I accomplish the above objects of the invention by means of the apparatus illustrated in the accompanying drawings, forming a part hereof, in which—

Figure 1 is a top or plan view of a section of a railway track where it intersects or crosses a street or highway, showing my safety gate and actuating mechanism in operative position. Fig. 2 is an enlarged detail view of the device which controls the lowering and raising of the safety gate, the same being shown on a considerably enlarged scale. Fig. 3 is a top or plan view of one of the boxes for enclosing the sheaves around which the gate actuating cables pass. Fig. 4 is a top or plan view of one of the trip devices. Fig. 5 is a side elevation of one of the trip devices, on the dotted line 5—5 in Fig. 4. Fig. 6 is an enlarged detail sec-

tional view of the tower for supporting the gate, showing the relative position of the gate-operating mechanism located therein, on the line 6—6 in Fig. 7. Fig. 7 is a cross section on the line 7—7 in Fig. 6. Fig. 8 is an enlarged detail horizontal sectional view of the driving and ratchet mechanism located on the gate-operating shaft, on the line 8—8 in Fig. 6. Fig. 9 is a longitudinal sectional view through the cable-winding drums and sleeve. Fig. 10 is a side elevation of the device attached to the train for operating the safety gate.

Referring to the drawings, the apparatus comprises the usual and well known tower 10, located at one side of the street or highway, the said tower forming a hollow casting for mounting the gate and inclosing the mechanism for operating the gate. Mounted transversely in the upper end of the tower 10 is the shaft 11, the ends of said shaft projecting outside of the tower to which the usual gate 12 is attached. The shaft 11 is provided with a sprocket-wheel 14 which is loosely mounted thereon, and said sprocket wheel is operated by means of a sprocket-chain 15 which extends downwardly and engages a sprocket-wheel 16 secured to a drum 17 which is loosely mounted on a transverse drum-carrying shaft 20. The drum 17 forms a repository for a spring 22 the outer end of which is attached to the drum while the inner end of the spring 22 is attached to a sleeve 23 which is loosely mounted on the drum shaft 20. The outer end of the sleeve 23 terminates in an enlargement forming a winding drum 25 around which an operating cable 26 is wound, and the drum 25 is provided with an integral flange 27 to prevent accidental displacement of the cable 26 as the latter plays off and on.

Referring to Fig. 1, it will be noted that the cable 26 extends quite a distance parallel with the track A where it engages a suitable actuating lever comprising a bent rock-shaft 30 which is mounted in suitable bearings 31 and held against longitudinal movement by the collars 32. The end of the rock-shaft 30 farthermost from the track A is bent downwardly (see Fig. 5), the lower end of which is provided with an adjustable weight 33 whereby the sheave 36, mounted on the end of the rock-shaft 30 adjacent to the track A, is returned to a determined po-

110

sition after being acted upon by the passing train. The cable 26 is secured to a bolt 35 passing through the weight 33 and by means of the lock-nuts 37 a tension may be maintained on said cable. When a train is moving in the direction of the arrow in Fig. 1, the rock-shaft 30 is actuated and a pull applied to the cable 26, causing a certain length of said cable to be unwound from the drum 25 and at the same time causes a portion of the inner end of the spring 22 to be wound about the sleeve 23. This winding up of the sleeve 22 increases its strength and power of action which is exerted throughout its length and applied to the drum 17, causing the latter to move in the direction indicated by the arrow in Fig. 6. This direction of movement of the drum 17 imparts a like movement of rotation to the sprocket-wheel 14 and through the latter's connection with the shaft 11, through certain ratchet and pawl devices which will be hereinafter described, the gate 12 is lowered to guard the street or highway. In order to hold the gate down for a given time and to raise the gate at the desired time, I interpose within the cable 26 a controlling device shown in Fig. 2. This controlling device contemplates the use of a movable trigger 50 which is moved back and forth within a suitable slot 51 in the casing 52. When the train is running at a high rate of speed a severe blow is imparted to the rock-shaft 30 when the sheave 36 is engaged, and through the rocking of the shaft 30 the cable 26 is initially drawn in the direction of the arrow in Fig. 2, so that the trigger 50 is moved from one end of the slot 51 to the position shown in Fig. 2, at which point the trigger is held locked by means of a transverse movable pawl 55 engaging the shoulder 56. The pawl 55 is normally held into contact with the adjacent edge of the movable trigger 50 by means of a spring 55. This sudden movement of the cable 26, while being imparted to the drum 25, will not be transferred to the drum 17 on account of the length of the intervening flexible spring 22, the shock being absorbed by said spring, and as the draw on the cable 26 is of determined length at each operation of the rock-shaft 30 a corresponding amount of rotation is imparted to the sleeve 23, causing a determined portion of the length of the spring 22 to be wound about said sleeve 23, so that the strength of the spring 22 is increased a determined amount and, in consequence, it exerts a determined amount of power to the drum 17, causing said drum to rotate, and through the sprocket-chain 15, sprocket-wheel 14 and shaft 11 the gate 12 is lowered at a determined rate of speed at all times. Until the trigger 50 is unlocked, a constant pull through the cable 26 is exerted upon the drum 25, causing the gate 12 to be held

down, and not until the pawl 55 is unlatched from the trigger 50 is the tension released from said drum 25, permitting the gate 12 to raise into vertical position. As the trigger 50 will move rapidly toward the left in Fig. 2 when released by the pawl 55, I provide a cushion for decreasing the force of the blow against the casing 52. This cushion consists of a sleeve 60 loosely mounted on the guide-rod 61 which connects one end of the cable 26 with the movable trigger 50, and a spring 63 which absorbs the shock when a blow is delivered upon the sleeve 60 by the released trigger 50. The other end of the cable 26 is secured to the guide-rod 62 attached to the opposite end of the trigger 50 from the guide-rod 61.

When the engine has passed the highway B a certain distance the rock-shaft 40 is actuated, and by means of the trip-cable 41, which connects the rock-shaft 40 and pawl 55, the latter is moved to unlatch the trigger 50 and allowing said trigger to move to the opposite end of the slot 51 and slack the cable 26. The sleeve 23, drum 17, sprocket-wheel 14 and shaft 11, all working in unison, and the resistance of the cable 26 being removed when the trigger 50 is unlatched, will cause the gate 12 to be elevated under the influence of the counter-weights 43.

The description so far relates to a train moving from right to left in Fig. 1. In order to increase the efficiency of a safety gate for the purpose herein set forth, it is desirable that the same shall be operated when the train is moving in the opposite direction, from left to right in Fig. 1. This is accomplished by means of a rock-shaft 70, similar to the rock-shaft 30, which is mounted along the track some distance from the crossing B, and this rock-shaft is connected to the guide-rod 62 by means of a cable 65 which passes around suitable sheaves located in the sheave-boxes 68 and 69. The construction of the sheave-boxes and sheaves is best shown in Fig. 3. When the rock-shaft 70 is actuated by the train the movable trigger 50 is set in the same manner as has heretofore been described in connection with the rock-shaft 30. After the engine has passed crossing B it engages the rock-shaft 80, similar to rock-shaft 40, which is connected to the trigger 50 by means of the trip-cable 81, which passes through the sheave-boxes 82 and 83 to the pawl 55, whereby the latter is retracted to release the movable trigger 50 in the same manner as has heretofore been described in connection with the rock-shaft 40.

As has heretofore been pointed out the safety gate 12 is lowered by the power applied through the spring 22, and that the gate is raised by means of the weights 43. In order that the gate may be easily operated the tension of the spring 22 is increased to

correspond to the resistance offered by the balance-weights 43 and gate body, so that only a slight additional increase in the power of the spring—induced through its winding 5 on the sleeve 23 by a pull on the cable 26—is necessary to cause the gate to be lowered. To enable the tension of the spring 22 to be increased, for the purposes heretofore set forth, without disturbing the relation of the 10 gate 12 and the shaft 11, the sprocket-wheel 14 and ratchet-wheel 90, which are secured together, are both loosely mounted on the shaft 11. This ratchet-wheel 90 is engaged by means of a pawl 91 supported by an arm 15 92 on the collar 93 which is rigidly attached to and moves with the shaft 11. When it is desired to increase the tension of the spring 22 the ratchet-wheel 90 and sprocket-wheel 14 are moved in the direction indicated by the arrow in Fig. 4 which imparts a like direction of movement to the drum 17, whereby the outer end of the spring 22 is moved to coil the spring 22 about the sleeve 23, the sleeve at this time being held against 25 rotation by the cable 26.

As has heretofore been stated, the rock-shafts are actuated by the trains, and to prevent injury to the parts of the mechanism the device of the train consists of a loop or 30 block 100 the edges of which are cut on an incline that engage the sheaves 36. The most desirable construction of the device on the train for actuating the rock-shafts is illustrated in Fig. 10.

Having thus fully described my said invention, what I desire to secure by Letters Patent, is—

1. In a railway crossing system, a track having a crossing, a vertically swinging gate 40 arranged near the crossing, a flexible element connected with the gate to move the same, trip-operated means arranged near the track at a suitable distance from the crossing and connected with the flexible element to move 45 it in one direction, a reciprocatory latch-member connected in the flexible element to move therewith, a releasable pawl engaging the reciprocatory latch-member to normally hold it against movement, a second flexible element connected with the pawl, and trip-operated means arranged near the track at a suitable distance from the crossing and connected with the second flexible element to move the same in one direction.

2. In a railway crossing system, a track having a crossing, a vertically swinging gate arranged near the crossing, a longitudinally extending flexible element connected with the swinging gate to move the same, trip-operated means arranged near the track at a

suitable distance from the crossing and connected with the flexible element to move the same, a reciprocatory latch-member connected in the flexible element and provided with a lateral stop-shoulder, a reciprocatory pawl operated at a right angle to the latch-member and adapted to releasably engage the stop-shoulder, a second flexible element connected with the pawl, and a trip-operated means arranged near the track at a suitable 65 distance from the crossing and connected with the second flexible element.

3. In apparatus of the character described, a support, a counterbalanced gate pivoted to the support to automatically swing in one 75 direction, pawl and ratchet mechanism to swing the gate in one direction, spring apparatus, connections between the spring apparatus and the pawl and ratchet mechanism, and trip operated means to actuate the spring 80 apparatus.

4. In apparatus of the character described, a support, a horizontal shaft journaled through the same, a counter-weighted swinging gate rigidly secured to the horizontal 85 shaft, a crank rigidly secured to the shaft, a pawl pivoted to the crank, a ratchet wheel loose upon the shaft and engaged by the pawl, a sleeve rotatable in the lower portion of the support, a drum loose upon the sleeve, 90 a coil spring within the drum with its ends attached to the sleeve and drum, trip operated means to turn the drum in one direction, and positive gearing connecting the sleeve and ratchet wheel.

5. In an automatic safety gate for railway crossings, a movable safety gate, a gate supporting shaft, power transmitting means loosely mounted on said shaft, a second shaft, revoluble means loosely mounted on said second shaft means for connecting the revoluble means on said second shaft and power transmission means on the gate supporting shaft, a cable-drum loosely mounted on said second shaft, means yieldingly connecting the cable-drum and revoluble means, means for rotating said drum in a direction to lower the gate, and a ratchet device carried by the gate supporting shaft for increasing the tension of the yieldable means for counterbalancing 100 the gate operating mechanism.

In witness whereof, I have hereunto set my hand and seal at Indianapolis, Indiana, this 3rd day of March, A. D., one thousand nine hundred and fourteen.

BERT C. SUITS. [L. s.]
